COMBINED CUTTER AND ADVERTISING DEVICE

Richard D. Elliott, Ahoskie, N. C., assignor of
one-third to J. Bailey Barnes, Ahoskie, N. C.

Application November 13, 1935, Serial No. 49,601

1. Claim. (Cl. 30—2)

This invention relates to a combined cutter and advertising device and has for its object to provide, in a manner as hereinafter set forth, a device of the class referred to for cutting open a cigarette package, as well as for displaying the package of cigarettes or other article of merchandise for advertising purposes.

Further objects of the invention are to provide, in a manner as hereinafter set forth, a combined cutter and advertising device for the purpose referred to which is simple in its construction and arrangement, strong, durable, compact, attractive, thoroughly efficient in its use, capable of distinctly displaying for advertising purposes an article of merchandise, having means for holding a package of cigarettes prior to and after the latter has been cut open, and inexpensive to manufacture.

With the foregoing objects in view and others which may hereinafter appear, the invention consists of the novel construction, combination and arrangement of parts as will be more specifically referred to and as are illustrated in the accompanying drawing wherein is shown an embodiment of the invention, but it is to be understood that changes, variations, and modifications may be resorted to which fall within the scope of the invention as claimed.

In the drawing:

Figure 1 is a top plan view of the device,
Figure 2 is a section on line 2—2, Figure 1,
Figure 3 is a section on line 3—3, Figure 1,
Figure 4 is a top plan view of the cutter blade,
and
Figure 5 is a sectional detail illustrating the cutter blade.

The device consists of a unit having a base section 1 and a top section 2. The said sections are formed of any suitable material, contrasting or otherwise. The sections 1, 2 may be of any suitable contour, but preferably are as shown, rectangular. The section 1 has its end edges 3, 4 and its side edges 5, 6 inwardly beveled from its lower to its upper face. The section 2 has its end edges 7, 8 and its side edges 9, 10 inwardly beveled from its lower to its upper face. The upper face of section 1 is of the same area as the lower face of section 2. The height of section 1 is less than that of section 2 and preferably the height of the latter will correspond to the thickness of a cigarette package. The section 2 is mounted in superimposed relation upon the section 1. The bottom of the side and end edges of section 2 are flush with the top of the side and end edges of the section 1. The sections 1 and 2 are secured together

by spaced holdfast devices 11 extending upwardly through section 1 and engaging in the section 2. The devices 11 are countersunk in the bottom of section 1. The securing of the sections 1 and 2 together provides a rectangular unit having its side and end edges beveled inwardly from its bottom to its upper face.

The upper face of section 1, between its lengthwise median and one side and its transverse median and one end, is formed with a plurality of 10 spaced sockets 12. The section 2, lengthwise thereof, is formed with a rectangular opening 13 having its outer end wall 14 arranged in close proximity to the end 7 of said section 2. The section 2, between the end 8 thereof and the inner 15 end wall 15 of opening 13, is formed with a circular opening 16 having its circular side wall 17 spaced from the sides and end 8 of section 2, as well as from the wall 14. The diameter of the opening 16 is approximately equal to the width of a cigarette package. The wall 17 of opening 16 at its lower end is rabbeted for a part of its circumference, as at 18. The sockets 12 open into the rabbeted portion 18 of wall 17. The section 1 coacts with the opening 13 to form the unit with 20 a rectangular compartment for receiving the article of merchandise to be displayed or the cigarette package prior and subsequent to cutting it open. The section 1 provides an end wall for the opening 16, and coacts with the opening 16 to provide a circular compartment for receiving a cigarette package inserted endwise with the wall 17 in snug engagement with the side edges of the package. Thus the inserted package may be rotated 25 within the recess, and when so rotated, the snug 30 engagement of the wall 17 with the side edges of the package will prevent lateral displacement of the package. The section 1 coacts with the rabbeted portion 18 of wall 17 to form a segmental shaped socket 19 which opens into the cutter 35 compartment.

Mounted in the socket 19 and permanently extending into the package receiving compartment is a cutter 20 formed of a substantially ovoidal shaped blade 21 having a substantially segmental 45 shaped cutting edge 22. The blade 21 in proximity to its non-cutting edge 23 is formed with a plurality of spaced openings 24. Positioned against each face of blade 21 is a narrow spacer strip. The strips are indicated at 25, 26 and have their 50 outer side edges flush with the edge 23 of the blade. The ends of the strips align with each other as well as being flush with the end terminal portions of the edge 22. The strips are arranged within and are of a width and length to corre- 55

spond to the width and length of the socket 19. The strip 25 abuts the top wall and the strip 26 seats upon the bottom wall of socket 19. The strips are formed with aligning openings 27 which register with the openings 24. Secured in the sockets 12 and in the openings 24 and 27 are anchoring pins 28 functioning to couple the cutter 20 to section 1. Secured in the sockets 12 and in the openings 24 and 27 are anchoring pins 28 functioning to couple the cutter 20 to section 1. The strip 25 acts to maintain the blade 21 permanently spaced above the bottom, formed by section 1 of the cutter compartment. The strip 26 acts to permanently space the blade 21 from the top wall of socket 19. The strips 25, 26 are flush with the wall 17 of opening 16.

To open a cigarette package, the package is placed in the cutter compartment with the end thereof to be opened down, and with the cutter 20 disposed at one side of the package. By turning the package within the opening 16 either clockwise or counter-clockwise, the stationary blade 21 cuts the end of the package. The strip 25 acts to control the point of the package in which the cut is made, and it is of a thickness to prevent the severing of the cigarettes when the package is cut open.

What I claim is:

A device for the purpose set forth, a base section, a top section superimposed upon and fixedly secured to the base section, said top section being formed with a vertically disposed opening, the wall of said opening coating with a part of the upper face of the base section to provide a vertically disposed recess opening at its upper end, the lower portion of the wall of said opening being formed with a rabbet for a part of its length, said rabbet coating with another part of the upper face of the base section to provide a socket opening into said recess at the bottom of the latter, a cutter mounted in and extended from said socket into said recess, superposed strips within and for spacing the cutter from the top and bottom walls of said socket, and spaced means carried by and extending upwardly from the base section, passing through said cutter and engaging with said strips for anchoring the cutter to said base section.

RICHARD D. ELLIOTT.
